UNITED STATES PATENT OFFICE.

LEWIS A. HARDISON, OF DUKE CENTRE, PENNSYLVANIA.

MACHINE FOR DRILLING WELLS.

SPECIFICATION forming part of Letters Patent No. 274,120, dated March 20, 1882.

Application filed March 31, 1882. Renewed January 2, 1883. (No model.)

To all whom it may concern:

Be it known that I, LEWIS A. HARDISON, a citizen of the United States, residing at Duke Centre, in the county of McKean and State of Pennsylvania, have invented a new and useful Machine for Drilling Wells, of which the following is a description and specification.

My invention relates to that part of a drilling-rig between the well and engine-pulley, and in the accompanying drawings, which is made a part of this specification, the engine or apparatus transmitting power to the band-wheel is not illustrated, as it constitutes no part of this invention.

The object of this invention is to afford a simple, cheap, and portable machine for drilling wells. I attain this object by the mechanism illustrated in the accompanying drawings, in which—

Figure 1 is a side elevation of the machine built upon a platform and that resting upon trucks. Fig. 2 is a top view of the same.

Similar letters relate to similar parts throughout the views.

a is a band-wheel, which receives the power from the engine by means of a belt or band and transmits it to the other parts of the machine in the manner hereinafter described.

b is the bull-wheel, attached to the axle *n*, upon which the drilling-cable is attached and wound.

k is the drilling-cable, one end wound around the bull-wheel shaft *n*, running thence through the temper-screw and cross-head *e*, thence under the pulley *f* and over the pulley *g*, and its extremity attached to the tools *l*.

c is a friction-wheel attached to the axle *o*, upon which the sand or bailer line *k'* is wound at one end, the other end extending to the derrick. This line is to run over a pulley in the derrick, which pulley is not shown in the drawings.

a' is a friction-wheel attached to the axle of the band-wheel *a*, and is used in turning the bull-wheel *b*.

j j' are suspended levers supported by pins attached to the upright posts, so as to be moved backward and forward by means of pitmen attached to the hand-levers *h h'* at one end, the others attached to the long arms of the

suspended levers. Into these suspended levers one of the gudgeons of the axles of the bull-wheel *b* and friction-wheel *c* are fixed, respectively.

m is the guide upon which the cross-head *e* plays.

The machine is operated as follows: We apply the hand at the lever *h* and move it backward until the bull-wheel *b* no longer rests against the friction-wheel *a'*, then apply the power and cause the band-wheel *a* to revolve. As the band-wheel revolves by means of the crank and pitman connecting the band-wheel axle with the cross-head *e*, which is in turn made fast to the cable *k*, the cross-head *e* is caused to move forward and back, which in turn, by the action of the cable moving under and over the pulleys *f* and *g*, gives an upward and downward motion to the tools *l*. As the depth of the well increases the cable must be let out, which is done by turning the temper-screw to which the cable is made fast in the cross-head *e*.

When it becomes necessary to clean out the mud and sand accumulated in the well by the drilling, we draw out the tools in the following manner: Remove the end of the pitman from the band-wheel crank, loosen the cable from the temper-screw at cross-head *e*, apply the hand at the lever *h*, and throw the bull-wheel *b* against the friction-wheel *a'*, which, when the band-wheel is again put in motion, will cause the cable to be wound upon the shaft *n* and the tools drawn from the well. We then attach the bailer to the line *k'* and let it fall to the bottom of the well by gravitation. Then, to raise the bailer, we apply the hand at the lever *h'*, throw the friction-wheel *c* against the band-wheel *a*, which causes the axle *o* to turn and wind the line *k'* until the bailer is out of the well, when we reverse the lever, empty the bailer, and repeat the operation until the mud, &c., is removed, when we again connect the pitman with the crank of the band-wheel axle, lower the tools, make fast the cable to the temper-screw, and again apply the power, and the drilling is thus effected.

What I claim as my invention, and desire to secure by Letters Patent, is—

1. A portable machine for drilling wells,

having a cross-head, *e*, running upon horizontal guides *m m*, combined with a temper-screw by which the cable is adjusted while in the operation of drilling, substantially as described and set forth.

5 2. In a portable machine for drilling wells, the combination of the band-wheel *a*, friction-

wheels *a'* and *c*, bull-wheel *b*, and cross-head *e*, substantially as herein described and specified.

LEWIS A. HARDISON.
